UNITED STATES PATENT OFFICE.

JOHN J. SHILLER, OF ROWENA, TEXAS.

CHIMNEY-PROTECTOR.

1,179,234.

Specification of Letters Patent. Patented Apr. 11, 1916.

Application filed June 25, 1915. Serial No. 36,311.

To all whom it may concern:

Be it known that I, JOHN J. SHILLER, a citizen of the United States, residing at Rowena, in the county of Runnels and State of Texas, have invented new and useful Improvements in Chimney-Protectors, of which the following is a specification.

This invention relates to chimney protectors especially adapted to be used in oil cooking stoves and it consists in the novel features hereinafter described and claimed.

An object of the invention is to provide a protector in the form of a single piece of material, easy and cheap to manufacture which, when applied to the chimney top of an oil cooking stove will prevent the drippings or overflow from utensils placed on top of the stove from running down the side of the chimney and injuring the same or obscuring the transparency with which the chimney is provided.

With the above object in view the protector is in the form of a circular pan having at its center an opening which is surrounded by a depending flange. The said flange is adapted to fit within the top portion of the chimney. The pan is provided with concentric inner and outer wall portions, which converge downwardly toward each other and serve as means for directing any liquid which may fall upon the pan, upon the bottom portion thereof and between the said converging side portions.

In the accompanying drawing:—Figure 35 1 is a detail sectional view of a portion of an oil cooking stove, showing the chimney protector applied thereto. Fig. 2 is a top plan view of the protector. Fig. 3 is a transverse sectional view of the same.

40 The stove to which the protector is applied includes a chimney 1 having a mica cover transparency 2. The upper end 3 of the chimney 1 is approximately conical (not shown).

45 The protector is in the form of a pan 4 open at its center as at 5. The opening 5 is surrounded by a depending annular flange 6 which is adapted to fit in the upper end of the chimney 1 when the protector is applied thereto. The pan also includes an inner wall 7 and an outer wall 8. These walls are concentrically positioned with relation to each other and are spaced from each other by the

bottom of the pan. The walls 7 and 8 converge downwardly toward each other. 55 When the protector is in position upon the upper end of the chimney 4 the wall 7 rests upon the cone-shaped upper end 3 of the said chimney.

When the protector is in position upon the upper end of the chimney and in the event that liquid should overflow from any of the utensils on top of the stove, the said overflow will precipitate and fall into the pan and is directed by the converging side 60 walls thereof upon the bottom of the pan. Thus the liquid cannot come in contact with the chimney and the transparency thereof. As these chimneys are usually provided with glazed surfaces any liquid which touches the 70 same while the chimney is hot cracks and mutilates the glazing and thus causes it to chip off. Also should the liquid come in contact with the mica transparency the same is rendered opaque and useless. The protector 75 may be readily removed from the chimney at any time for cleansing or other purposes. Therefore it will be seen that a chimney protector of simple structure is provided and that the same will efficiently operate to protect the chimney against drippings from the top of a stove.

Having described the invention what is claimed is:—

In combination with a chimney, a protector formed from a single piece of material having an open center, the said protector being in the form of a pan having downwardly converging inner and outer walls and provided with an annular flange surrounding 85 the opening at the center, the surface of the said flange being disposed perpendicular to the plane in which the bottom of the pan lies and fitting snugly in the chimney and holding the protector in position thereon with the inner converging wall of the pan disposed over the upper edge of the chimney, the lower edge of the flange lying in the same plane as that in which the bottom of the pan lies. 95

In testimony whereof I affix my signature in presence of two witnesses.

JOHN J. SHILLER.
